UNITED STATES PATENT OFFICE.

JOHN W. ESHELMAN, OF BROOKLYN, NEW YORK.

MACHINE FOR EXTRACTING THREADS FROM WOVEN FABRICS.

1,261,373.

Specification of Letters Patent.

Patented Apr. 2, 1918.

Application filed September 2, 1914. Serial No. 859,813.

To all whom it may concern:

Be it known that I, JOHN W. ESHELMAN, a citizen of the United States, and resident of the borough of Brooklyn, in the city and 5 State of New York, have invented a new and useful Improvement in Machines for Extracting Threads from Woven Fabrics, of which the following is a specification.

The object of this invention is to provide 10 certain improvements in the construction, form and arrangement of different parts of a machine for extracting threads from woven fabrics whereby the threads to be extracted may be accurately and surely deflected from the plane of the body of the 15 fabric with the least possible disturbance to the body of the fabric and such deflected threads entirely and rapidly removed.

My invention more particularly includes 20 means for holding the fabric firmly in position while being operated upon by the thread deflecting and cutting mechanisms; a suitable guard for the deflecting blade; a deflecting blade having a plurality of 25 branches; a cutter plate having its under surface shaped to coat with a knife set parallel with the axis of its shaft; and a cutter plate having a plurality of holes corresponding to the number of prongs of the thread 30 deflecting blade.

A practical embodiment of my invention is represented in the accompanying drawings, in which only so much of a machine of the above character is illustrated as will 35 give a clear understanding of my improvements.

Figure 1 represents the machine in front elevation with certain of the parts broken away,

40 Fig. 2 is a view of the machine in end elevation partly in section, with the cover plate for the head removed,

Fig. 3 is a detail section showing the 45 thread deflecting blade and the guard therefor,

Fig. 4 is a detail vertical section on an enlarged scale of the parts shown in section in Fig. 2,

50 Fig. 5 is a detail horizontal section taken in the plane of the line A—A of Fig. 4, with the deflecting blade and guard removed,

Fig. 6 is a detail plan view taken in the plane of the line B—B of Fig. 4,

55 Fig. 7 is an inverted plan view of the cutter plate,

Fig. 8 is a detail transverse vertical section taken in the plane of the line C—C of Fig. 4,

Fig. 9 is a detail transverse section taken 60 in the plane of the line D—D of Fig. 5,

Fig. 10 is a plan view of the knife,

Fig. 11 is a detail section taken in the plane of the line E—E of Fig. 4,

Fig. 12 is a detail plan view of the cutter 65 head, cutter and shaft,

Figs. 13 and 14 are detail front and edge views, respectively, of the lower end of the deflecting blade,

Fig. 15 is a front view of the lower end 70 of a deflecting blade of slightly modified form,

Fig. 16 is a top plan view of a cutter 75 plate adapted to the blade shown in Fig. 15, and

Fig. 17 is a detail sectional view of the cutter plate on a greatly enlarged scale with the path of the cutting edge of the knife indicated in connection therewith.

The machine table 1, upright 2, overhanging arm 3, head 4, upper horizontally disposed rotary shaft 5, needle bar 6, presser bar 7, its divided presser foot 8 and feed plate 9, are of well known or approved construction and need not be specifically described herein.

A lower horizontally arranged cutter shaft 10 is mounted beneath the table 1 and is driven, in the present instance, at twice the rotary speed of the shaft 5 through a 90 belt and pulley connection 11, 12, 13. This cutter shaft 10 is provided with a head 14 having a seat 15 for the knife 16, which seat is disposed parallel to the axis of the rotary shaft 10. The knife 16 is secured 95 to the head 14 by means of a suitable fastening screw 17 which passes through an elongated slot 18 in the knife. The head 14 is provided with a lip 19 forming a guide for one of the side edges of the knife. The 100 knife 16 has a diagonal cutting edge 20 beveled on its inner face to present a sharp cutting edge.

The parallelism of the knife seat with the axis of the rotary shaft and the diagonal 105 cutting edge of the knife combine to cause the cutting edge of the knife to travel in a circular path inclined with respect to the axis of the said rotary shaft.

The cutter plate is denoted by 21 and it is 110 secured in the proper position on the table 1 with respect to the rotary cutter by suit-

able fastening screws 22. This plate has a plurality of transversely elongated holes 23 therethrough in position to receive a plurality of prongs at the lower end of the deflecting blade to be hereinafter described.

5 The under surface of the cutter plate 21 is cut away in the plane of the rotary cutter to conform to the angularity of the cutting edge of the knife with respect to the shaft 10 so that the cutting edge 20 of the knife will first come into engagement with the cutter plate as the edge reaches the holes 23 and leaves its engagement with the cutter plate as the edge passes beyond the said 15 holes.

A slight ridge 24 is formed in the under surface of the plate 21 adjacent to the holes 23 which ridge projects slightly into the path of the cutting edge 20 of the knife 20 16 so that the said cutting edge is slightly deflected for a very short portion of its rotary movement thereby causing the edge to be self-sharpening and maintaining the edge at a high degree of cutting efficiency. 25 The cutaway surfaces 25 and 26 to the front and rear of the ridge 24 are so arranged that the cutting edge 20 of the knife has a free movement up to the hole 23 and a free movement after it leaves the ridge 24, this 30 latter free movement serving also to insure the free removal of the deflected threads separated from the fabric by the knife.

The thread deflecting blade is denoted by 27 and its lower end is flattened transversely 35 of the line of feed of the machine and is provided with a plurality of prongs 28 each having a diagonal bottom straight edge for facilitating the entry of the prongs between the crosswise threads of the fabric. Each 40 prong 28 has a notch 29 near the upper end of the diagonal straight edge, which notch serves to engage the same longitudinal thread of the fabric for insuring the proper number of longitudinal threads being deflected by the blade. 45

The number of prongs 28 of the deflecting blade correspond to the number of holes 23 in the cutter plate 21. This blade is attached to the vertically reciprocating needle bar 6 passing through a transverse hole 30 in the divided presser foot 8 and also through the transverse holes 23 in the cutter plate 21.

50 Means are provided for holding the fabric taut as it passes between the cutter plate and divided presser foot, which means is herein shown as comprising lugs 31 on the cutter plate 21 opposite shallow recesses 32 in the sides of the divided presser foot 8. 55 The sides of the divided presser foot are beveled and the adjacent sides of the lugs 31 are undercut so that as the fabric is passed over the lugs 31 and under the divided presser foot, the portion of the fabric passing 60 between the divided presser foot and the

cutter plate is held taut thereby insuring the accurate deflection of the required number of threads by the prongs of the deflector blade.

A suitable tubular finger guard 33 surrounds the deflector blade 27, which guard is secured to the needle bar 6 by a suitable fastening screw 34. This guard extends downwardly to within a short distance of the divided presser foot 8 and is provided with a longitudinal slot 35 for permitting access to the screw 36 which fastens the deflecting blade to the needle bar.

The movements of the cutter with respect to the deflecting blade are so timed that the 80 prongs of the deflecting blade will force the required number of longitudinal threads downwardly through the holes 23 and the prongs are then withdrawn before the said deflected threads are acted upon by the knife 85 of the rotary cutter in its first revolution. The knife of the rotary cutter is again caused to engage said deflected threads during its second revolution for insuring the removal of any of the deflected threads 90 which were not cleanly removed by the knife in the first revolution of the cutter.

95 After this second revolution of the cutter, the deflecting blade again forces the threads beyond the next succeeding transverse thread or threads, downwardly through the holes 23, it being understood that the fabric is moved step by step rearwardly by the feeding mechanism in the usual manner.

100 It is to be understood that the number of prongs on the deflecting blade may be varied to suit different requirements and that the width of each prong may be varied so that any desired number of threads within reasonable limits may be removed.

105 It is evident that slight changes may be resorted to without departing from the spirit and scope of my invention; hence I do not wish to limit myself strictly to the structure herein set forth, but

110 What I claim is:—

115 1. In a machine of the character described, a thread deflecting blade having a plurality of thread engaging prongs of predetermined widths and separated from each other by predetermined distances for acting upon predetermined separated threads or separated groups of threads.

120 2. In a machine of the character described, a thread deflecting blade having a plurality of thread engaging prongs of predetermined widths and separated from each other by predetermined distances for acting upon predetermined separated threads or separated groups of threads, each prong having 125 an inclined bottom edge for facilitating the entry of the prongs between the crosswise threads of the fabric.

130 3. In a machine of the character described, a thread deflecting blade having a plurality

of thread engaging prongs of predetermined widths and separated from each other by predetermined distances for acting upon predetermined threads or groups of threads, each prong having an inclined bottom edge for facilitating the entry of the prongs between the crosswise threads of the fabric, and a notch at the inner end of such edge for insuring the proper number of longitudinal threads being deflected by the blade.

4. In a machine of the character described, a cutter plate having a plurality of holes therethrough, a thread deflecting blade having a plurality of prongs corresponding to the number of holes in the cutter plate for forcing the threads to be removed through said holes and means for removing the deflected threads.

5. In a machine of the character described, a cutter plate, thread deflecting means for forcing the threads to be removed through said plate, a rotary shaft, a cutter head thereon and a knife seated on said head parallel with the axis of the shaft, said knife having a diagonal cutting edge traveling in a circular path inclined with respect to the axis of the rotary shaft, and said cutter plate having its under side cut away to conform to the angularity of the cutting edge of the knife with respect to the rotary shaft, to insure a proper coaction between the knife and cutter plate for removing the deflected threads.

6. In a machine of the character described, a cutter plate, a needle bar, a reciprocating

thread deflecting blade for forcing the threads to be removed through said plate, a screw for fastening the deflecting blade to the needle bar, means for removing the deflected threads and a tubular finger-guard surrounding said deflecting blade and having a longitudinal slot for permitting access to said screw.

7. In a machine of the character described, a presser foot, a cutter plate, thread deflecting means for forcing the threads to be removed through said plate, means for removing the deflected thread and lugs on the cutter plate coacting with said presser foot for exerting lateral strain on the fabric to hold it taut as it is operated upon by the thread deflecting means.

8. In a machine of the character described, a presser foot having shallow recesses in its side edges, a cutter plate, thread deflecting means for forcing the threads to be removed through said plate, means for removing the deflected threads and lugs on the cutter plate, coacting with said recesses in the presser foot for exerting lateral strain on the fabric to hold it taut as it is operated upon by the thread deflecting means.

In testimony, that I claim the foregoing as my invention, I have signed my name, in presence of two witnesses, this first day of September, 1914.

JOHN W. ESHELMAN.
